UNITED STATES PATENT OFFICE.

CHARLES F. STAPLES, OF DETROIT, MICHIGAN.

WASHING MACHINE.

Application filed June 4, 1921. Serial No. 474,906.

To all whom it may concern:

Be it known that I, CHARLES F. STAPLES, a citizen of the United States, residing at Detroit, county of Wayne, State of Michigan, have invented a certain new and useful Improvement in Washing Machines, and declare the following to be a full, clear, and exact description of the same, such as will enable others skilled in the art to which it pertains to make and use the same, reference being had to the accompanying drawings, which form a part of this specification.

My invention relates to washing machines. The object is to provide a unitary washer and centrifugal dryer of simple, inexpensive construction adapted for concurrent operation from the same source of power supply.

A further object is to provide, in combination with a vacuum cup type of washing machine, a centrifugal drying basket adapted for rotation concurrently with the operation of the washer and driven by the same power impulses.

A further object is to provide a washing machine in which the centrifugal-drying basket superimposes the washing vat and is driven by the main drive shaft which extends through the vat and from which shaft is likewise driven the washing element contained in the vat.

A further object is to provide a washing machine having a centrifugal drying basket superimposing that portion of the vat in which the washing elements are disposed and adapted to discharge independently thereof.

These and other objects, together with details of construction will more fully appear from the following description, appended 40 claims and the accompanying drawings, in which:

Figure 1 is a vertical cross-section through my washing machine.

Fig. 2 is a plan view, the cover and drying basket being removed.

Fig. 3 is an enlarged fragmentary view partly in section of the end of the motor shaft and connected parts.

Fig. 4 is a spread-out plan of the bearing surface of the cross-arm showing the formation of the spiral groove.

Fig. 5 is an elevation of the driving cam carried by the drive shaft.

Fig. 6 is a horizontal section taken on the line 6-6 of Fig. 1.

In the drawing, let α indicate a washing

vat suitably supported by means of legs b and provided with a drain plug c . The vat casing is extended upwardly, here shown as a portion of enlarged diameter d which is provided with a cover d^2 and an independent discharge pipe d^3 .

Positioned below the vat is a motor e . Keyed on the motor shaft e^2 is a driving gear f . Gear f engages gear g^2 which is carried by the main drive shaft or spindle g , which spindle extends upwardly through the bottom of the vat. This spindle is suitably journaled within a housing h . Spring f^2 holds the gear f yieldingly against the gear g^2 , so as to maintain constant driving engagement therewith. Positioned within the casing d and detachably mounted on the driving spindle g for rotation is a centrifugal drying basket i perforated for the purpose desired, and provided with openings i^2 through which the clothes carried in the washing vat may be removed and placed in the dryer.

Sleeved on the housing h for rotation is a cross-arm m held upwardly by means of the tension spring n , which spring is supported by a shoulder h^2 formed on the housing. This cross-arm carries at its extremities vacuum cups n^2 .

A cam member o is secured to the drive shaft g to rotate therewith and is likewise secured to the bottom of the centrifugal basket i forming a support therefor. The shape of this cam member is shown in Figs. 1 and 5. This cam engages the hub m^2 of the cross-arm m in such a manner that as the cam is rotated the cross-arm is depressed against the resistance of the spring n , producing a vertical reciprocation of the cross-arm concurrently with the rotation of the dryer.

To produce rotation of the cross-arm concurrently with its vertical reciprocation, the bearing face of the passageway through the hub of the cross-arm is provided with a zigzag groove q formed as shown in Fig. 4 which is an elevation of the interior surface of the hub rolled out flat. A pin p is secured to the housing h upon which the hub is journaled and is adapted to travel in this zigzag groove q as the cross-arm is vertically reciprocated. The travel of this pin in the groove q during the reciprocation of the cross-arm produces rotation of the cross-arm. It is apparent that the relative position of the groove and pin might be reversed,

the pin being carried by the cross-arm and the groove formed in the shaft. The bevel of the zigzag groove is such at the apices of the groove as to throw the pin off center as the cross-arm comes to the end of its stroke so that the cross-arm will travel continuously forward in a given direction.

In the operation of the machine, it will be seen that the cross-arm carrying the vacuum cups will rotate and reciprocate concurrently with the rotation of the drying basket.

What I claim is:

1. In a washing machine, the combination of a vat, a driving shaft extending upwardly through the bottom of the vat, a centrifugal drying basket positioned in the upper portion of the vat and mounted upon the drive shaft for rotation therewith, a rotatable reciprocating washing element mounted within said vat below said basket, spring means exerting an upward yielding pressure on said washing element, a cam member carried by said basket engaging said washing element and adapted to co-operate with the spring means to reciprocate the washing element as the basket is rotated, and means engaging said washing element to convert the reciprocal motion thereof into rotary motion.
2. In a washing machine, in combination, a vat comprising an upper portion of a diameter enlarged beyond the diameter of the lower portion and provided with an independent discharge outlet, a drive shaft extending through the bottom of said vat, and a drying basket mounted for rotation in the enlarged upper portion of the vat and per-

forated to drain in such enlarged upper portion only.

3. In a washing machine, in combination, 40 a cylindrical vat having an upper portion of a diameter enlarged over the lower portion, a drive shaft extending upwardly through the bottom of the vat, a perforate drying basket positioned in the upper portion of 45 the vat and mounted upon the drive shaft for rotation therewith said drying basket being of a greater diameter than the diameter of the lower portion of the vat, a rotatable reciprocating washing element positioned in 50 the lower portion of the vat and engaging said drying basket to be reciprocated as the basket is rotated, and means adapted to engage said washing element to rotate the same as it is reciprocated.

4. In a washing machine, in combination, 60 a cylindrical vat, a drive shaft extending through the bottom thereof, a centrifugal drying basket positioned in the upper portion of said vat and mounted upon said drive shaft to rotate therewith, a housing surrounding said drive shaft, a washing element mounted upon said housing for rotation and reciprocation, spring means adapted to normally support said washing element in the uppermost position in said housing, and a cam member rotatable with the drive shaft adapted to force the washing element downwardly against the resistance of said 65 spring means once for each complete rotation of the shaft.

In testimony whereof, I sign this specification.

CHARLES F. STAPLES.
